Attorney

UNITED STATES PATENT OFFICE.

FRED K. FINNEMAN, OF PORTLAND, OREGON.

SAW-CLAMP GUARD.

Application filed January 17, 1925. Serial No. 3,075.

To all whom it may concern:

Be it hereby known that I, FRED K. FINNEMAN, a citizen of the United States, and a resident of Portland, in the county of 5 Multnomah and State of Oregon (whose post-office address is 469 Clay Street), have invented a new and useful Saw-Clamp Guard, of which the following is a specification.

10 This invention relates generally to the art of filing saws, and particularly to the type of saw clamp in which the clamp passes around the toothed edge of the saw instead of around the back of the saw as is commonly the case.

15 The first object of this invention is to provide an exceedingly simple and efficient saw guard by means of which the saw teeth will be prevented from coming in contact with the clamp when shifting the position of the saw.

20 The second object is to render unnecessary the extreme care which the filer must employ when shifting his saw, thereby reducing the time of filing and enabling him to direct his attention to the object which he is trying to accomplish, namely the sharpening of the saw.

25 The third object is to prevent any of the saw teeth from becoming dulled by contact with the saw clamp, or, if resharpened, shorter than the adjacent teeth.

30 The fourth object is to so construct the device that it may be readily applied to the saw clamp, or replaced if worn out, without the aid of a special tool not ordinarily found in a carpenter's kit, and at the same time to render the device capable of being so securely fastened that it will not readily become 35 separated from the clamp.

35 These, and other objects, will become more apparent from the specification following as illustrated in the accompanying drawing, in which:

40 Figure 1 is a plan of the saw clamp showing my device attached. Figure 2 is a front elevation of the device as shown in Figure 1. Figure 3 is a side elevation of the device at a somewhat larger scale showing same attached to a table top or bench. Figure 4 is 45 a vertical section taken along the line 4—4 in Figure 3. Figure 5 is a front elevation of the device itself, of which Figure 6 is an end elevation and Figure 7 is a plan.

50 Similar numbers of reference refer to the same parts throughout the several views.

55 Referring in detail to the drawing, there is illustrated a type of saw clamp in which the clamp passes around the teeth 10 of a saw 11. The clamp itself consists of a longitudinal angle member 12 and a flat bar 13 which are tied together at their ends by the side frames 14 having channel shaped cross sections. On the member 12 is placed a rubber strip 15 which is secured by means 60 of a metal strip 16 which is held in place by the screws 17.

65 Between the down-turned ends 18 of the side frames 14 there is pivotally mounted an eccentric bar 19 provided with a handle 20. 70 A bench clamp arm 21 is attached to the angle iron 12 by means of a rivet 22 and is provided at its lowermost end with a clamping screw 23 having a handle 24 and a wood-engaging end 25.

75 Turning now to the guard itself, which is plainly illustrated in Figures 5, 6 and 7, it will be seen to consist of a somewhat rectangular block 26, preferably of rubber, and having a somewhat rounded edge 27, and is 80 provided with a thin strip of metal 28 which projects from each end of the member 26. The guards 26 are of such shape and size as to fit snugly into the openings between the side portions of the frames 14, and the 85 strips 28 are sufficiently long to permit their being clamped inwardly and downwardly against the upper sides of the frames 14, as shown in Figure 4.

85 The operation of the device is as follows: 90 The saw 11 is placed against the angle iron 12 and the eccentric bar 19 is rotated in a manner to securely clamp the saw in place in the position for filing. When it is desired to move the saw it is not necessary to 95 exert any special care to see that the teeth 10 do not become dulled by contact with metal, since the only object which they can touch is the under side of the guards 26.

100 It will be understood, of course, that the exact shape and size, as well as the kinds of hardware for attaching the guards 26 may be varied to suit the particular kind of side frame 14 with which they are employed: it being borne in mind, however, that the 105 guards above described are necessary only with the type of saw clamp in which the clamp members pass around the toothed edge of the saw as above suggested.

110 While the guard members have been referred to as being made of rubber, it must be understood that these may also be made

of any other material such as wood or composition which is sufficiently soft to prevent the teeth from being dulled when coming in contact with same.

5 I claim:

1. A guard for saw clamps consisting of a somewhat flat rectangular rubber block having a rounded edge; and a strip of metal passing through said rounded edge and pro-

jecting from each end thereof, said metal being parallel with the straight edge of said guard opposite said rounded edge. 10

2. A guard for saw clamps consisting of a somewhat rectangular rubber block having a somewhat rounded side; and a strip of metal passing through said rounded side and projecting from each end thereof. 15

FRED K. FINNEMAN.
